(57) **CLAIM**

The ornamental design for a rear combination lamp for cars, as shown and described.

DESCRIPTION

1. Rear combination lamp for cars
- 1.1 is a top, front, and right side perspective view of a rear combination lamp for cars showing our new design;
- 1.2 is a front elevation view thereof;
- 1.3 is a rear elevation view thereof;
- 1.4 is a left side elevation view thereof;
- 1.5 is a right side elevation view thereof;
- 1.6 is a top plan view thereof; and
- 1.7 is a bottom plan view thereof.
